Atty.

UNITED STATES PATENT OFFICE.

BERNARD P. SMITH, OF ST. LOUIS, MISSOURI

ADJUSTABLE DRAIN AND TRAP FOR REFRIGERATORS.

1,375,423.

Specification of Letters Patent. Patented Apr. 19, 1921.

Application filed January 5, 1921. Serial No. 435,260.

To all whom it may concern:

Be it known that I, BERNARD P. SMITH, a citizen of the United States, residing at St. Louis, in the State of Missouri, have invented certain new and useful Improvements in Adjustable Drains and Traps for Refrigerators, of which the following is a specification containing a full, clear, and exact description, reference being had to the accompanying drawings, forming a part hereof.

My invention consists in the novel construction and combination of parts herein-after particularly described and distinctly claimed.

The object of my invention is to provide an improved adjustable, detachable and swinging drip-pan and drain-trap, for household and store refrigerators; which will be of low cost and highly efficient in operation; which may be quickly installed upon the usual fixed drain-pipe or sewer connection already in the building; which will effectually trap all sewer gas, and prevent the discharge of same into the room containing the refrigerator; and which may be quickly swung around after installation, to receive the drain-water from the drip-spout or drip-pipe of various forms of refrigerators, no matter at what point beneath the refrigerator its drip-pipe may be located.

In the drawings,

Figure 1 is a vertical section of my improved drip-pan and drain-trap, applied to a household refrigerator sewer-connection, and

Fig. 2 is a front-elevation of the lower portion of a household refrigerator, with my drip-pan and drain-trap in position to catch the drain-water from the drip-pipe of the refrigerator.

The numeral 1 designates the horizontal arm of the drip-pan, the conical body 2 of which is provided with a tapered portion 3, which is mounted to revolve in an internally tapered bearing-nipple 4; the lower end of the latter being threaded into the upper end of the usual sewer or drain connection 5 projecting above the floor 6 of the room in which the refrigerator 7 is located.

Formed around the interior of the said bearing-nipple 4 is a U-shaped trap 8, which is filled with drip water during use and

forms a very effective seal against the passage of sewer-gas into the room through the joint between said bearing-nipple 4 and the 55 tapered journal portion 3, the lower end of the latter being submerged at all times during use in the water contained in said trap, as shown in Fig. 1.

Removably seated in the annular recess 60 9, at the upper end of said conical body 2 of the invention, is a common strainer-plate 10, which forms a bottom for the end of the pan which is opposite the said horizontal arm 1 thereof, but which can be readily 65 taken out for cleaning or repairing the parts of the well-known form of trap 11 that prevents the entrance to the room of sewer gas directly through the discharge member 12.

Said trap 11 is the main trap of the drip-pan, and it is located beneath said strainer-plate 10, on the interior of the said conical body 2. Its construction and function being well known, no further description thereof need be given, except to say that being 75 mounted to rotate, its location, and the conical shape of its exterior, are new so far as known to me.

It will be observed that a body of drip-water is contained in the said conical body 80 2, and rotates therewith whenever the said body is rotated, in changing the position of the drip-pan arm 1.

The operation.

The operation of my invention will be readily understood from the above description, and nothing further need be said, except that (as shown by the dotted lines in Fig. 2) the horizontal arm 1 of the drip-pan may be swung around in any direction, in a horizontal plane, so that the drip-water from the drip-pipe 14 may be received into said arm, no matter what the position of the refrigerator may be, without moving the 95 latter.

I claim:

An adjustable drip-pan for refrigerators, composed of a horizontal-arm portion, a conical body to which one end of said arm 100 is connected, a main gas-trap in said body, a strainer above said main gas-trap, a bearing-nipple to be connected to the drain-connection of the room, a U-shaped trap mem-

ber on the interior of said nipple, and a tapered portion at the lower end of said conical body, projecting downwardly into the said U-shaped trap member, and forming a seal thereat between said nipple and said lower end of the conical body, as the latter is rotated or rests within said nipple.

In testimony whereof, I have signed my name to this specification in the presence of two subscribing witnesses.

BERNARD P. SMITH.

Witnesses:

FRANCES E. MORRIS,
JOHN C. HIGDON.
